Application November 20, 1939, Serial No. 305,281

10 Claims. (Cl. 173—346)

This invention relates to improvements in switch and lamp units, and more particularly to switch and lamp units in which the switch mechanism is controlled by a door.

An object of the present invention is to provide a lamp and switch unit that shall be compact and simple in construction which may be readily manufactured and assembled at a low cost, and which, in use will prove efficient and convenient. These and other objects of the invention are obtainable by providing a switch and lamp unit including a metal socket member for receiving a lamp base having a metal sheath connected with one of the leads of the lamp filament and an end terminal connected with the other lead of the filament, the socket making electrical connection with the sheath. A switch comprising movable and stationary contacts with a spring located between the end terminal of the lamp base and the movable contact connects the lamp in a circuit. The spring operates to urge the movable contact into engagement with the stationary contact and also conduct current from the movable contact to the center terminal of the lamp base. A plunger of insulating material carries the movable contact and operates to separate the contacts to disconnect the lamp from the circuit and compress the spring when a door of a compartment is closed. When the door is opened the spring expands to urge the movable contact and plunger in a direction such that movable contact will engage the stationary contact.

Further objects and advantages of the present invention will be apparent from the following description, reference being had to the accompanying drawing wherein a preferred embodiment of the present invention is clearly shown.

In the drawing:

Fig. 1 is an elevational view showing a lamp and switch unit assembled in a housing with one wall of the housing removed.

Fig. 2 is a sectional view showing the switch construction and showing the device in its circuit open position.

Fig. 3 is a sectional view taken on the line 3—3 of Fig. 2.

Fig. 4 is a sectional view taken on the line 4—4 of Fig. 2.

Fig. 5 is a fragmentary sectional view taken on the line 5—5 of Fig. 2.

Referring to the drawing 20 designates a metal housing including a front wall 21, a back wall 22, side walls 23 and 24 and a bottom wall 25. Portions of the metal of the back wall 22 are

struck out and bent outwardly to form spaced arcuate projections 26, the wall 22 and each projection being further deformed to provide recesses 27 arranged opposite to each other. The projections 26 form a socket member to support a lamp 28 having a base including a metal sheath or a sleeve 29. The sheath 29 is connected with one lead of the lamp filament, the other lead of the lamp filament is connected with a contact 32 located adjacent and insulated from the rear end of the sheath 29. The sheath 29 carries pins 30 projecting from the sleeve adapted to be received by the recess 27 formed in the wall 22 and the projections 26.

15 A switch unit 35 for controlling the current to the lamp 28 is located within the housing 20. The switch unit 35 comprises a plate or support 36 of insulating material. The plate 36 is provided with an aperture 37 and a notch 38 extending radially from the marginal wall of the aperture 37. The plate 36 is provided with lateral ears or lugs 39 and a tongue 40.

A stationary contact 41 is fixed to the plate 36. The stationary contact comprises a disc portion 25 42 engaging the front face of the plate and having a tubular shank 43 extending through the aperture 37. The tubular portion 43 is riveted over on the rear face of the plate 36 to attach firmly the stationary contact to the plate. In order to prevent rotation of the stationary contact 41 with respect to the plate, a radial projection 44 integral with the disc portion has its free end bent at an angle and located in the recess or notch 38. A lead wire 45 is attached to the disc portion 42.

The tubular portion 43 of the stationary contact 41 slidably supports a hollow plunger 46 of insulating material. The plunger 46 includes a reduced portion 47 that is slideable within the tubular shank of the stationary contact and an enlarged portion 48 to form a shoulder 49, the shoulder operating to limit the movement of the plunger in one direction relative to the stationary contact. The plunger 46 is counterbored to form 40 an internal shoulder 50. The small diameter of the counterbore receives a movable tubular contact 51 one end of the contact is provided with a radial flange 52 adapted to project beyond the periphery of the small end of the plunger 46. The other end of the tubular contact is riveted over against the internal shoulder 50 to maintain the contact 51 assembled with the plunger 46. The radial flange 52 is of such dimension that it will engage the stationary contact 41 and also limit the movement of the plunger 47 in the

opposite direction with respect to the stationary contact 41.

A conducting rod 60 is slidably supported within the movable contact 51. The rod 60 comprises a head portion 61 adapted for engagement with the lamp contact 32 and a shaft portion 62. The shaft 62 projects beyond the riveted over portion of the movable contact 51 within the counterbore. The end of the shaft portion is flared out, as at 63, which serves as an abutment to limit the extent to which the rod 60 may be moved in one direction relative to the movable contact 51 and also to prevent the rod 60 from dropping away from the movable contact 51 when the switch unit is not assembled with the balance of the structure. A spring 64 is disposed between the head 61 and the radial flange 52 of the movable contact 51 and has one end abutting the head and the other end abutting the radial flange. The spring operates to press the head 61 against the contact 32 and also to urge the plunger 46 and the radial flange to the right as viewed in Figs. 1 and 2. The spring also operates to conduct current from the movable contact to the head 61. This is important especially when the contact engagement between the rod 62 and the shank of the movable contact is not positive.

The switch unit 35 is attached to the housing 20 by providing the housing bottom wall 25 with an aperture 10 to receive the tongue 40 of the plate 36. The side walls 23 and 24 are provided with angular flanges 71. The side walls are provided with notches 73 upon which rest the lateral lugs 39 of the plate 36. The notches 73 are formed by striking out portions of the metal in the side walls to form upstanding tangs 75, see Fig. 5, integral with the flange 71. When the plate 36 is properly placed within the housing 20, the tongue 40 will protrude through the aperture 10, the enlarged portion of the plunger will extend through a bearing 16 provided on the front wall 21, and the lugs 39 will fit in their respective notches 73, in the side walls 23 and 24, the tangs 75 are bent downwardly against the top edge of the plate 36, as clearly shown in Fig. 4. Thus the switch unit 35 is securely held within the housing 20 and the plunger 46 will be slidably supported by the bearing 16 and the tubular portion 43 of the stationary contact.

The flanges 71 formed integral with the side walls are also provided with apertures 11 through which bolts may pass for securing the housing to a wall, not shown, of a compartment. It is to be understood that the housing 20 is to be supported within the compartment so that the plunger 46 will be in close proximity to and actuated by a door for the compartment, a fragment of the door is indicated by the numeral 89, see Fig. 2.

The operation of the device will be readily understood as follows: Referring to Fig. 1, the switch and lamp unit is shown in its circuit closed position allowing current to flow from battery 81, lead 45, stationary contact 41, movable contact 51, rod 62 or spring 64 or both, head 61 center contact 32, the lamp filament, sheath 29, wall 22, and then back to the battery through ground connection 83. When the part 89 is actuated, the plunger 46 and the movable contact 51 are moved to the left the spring 64 will be compressed, see Fig. 2. When this happens the flanged portion 52 of the movable contact will be separated from the stationary contact 51 to open the circuit. When the door is opened the

spring 64 will expand and urge the movable contact and plunger to the right until the flange portion 52 engages the stationary contact 51 and then close the circuit to the lamp 28.

From the foregoing description of the construction and the method of assembly of the switch units it is apparent that I have provided a novel and improved switch and lamp unit of simple and compact construction which can be built economically. My new switch and lamp unit can be built in separate units. Furthermore, by building the separate units, it is possible to use the switch unit independently to handle other circuits, in which only one push button or actuator is required for control of the circuit. This invention in addition provides a novel switch construction having a plunger operating member slidably mounted in the stationary contact carrying the movable contact to engage and disengage the stationary contact. Thus the conductive parts of the switch are assembled in such a manner that the movable contact can not be accidentally lost when the switch structure is not assembled with the balance of the structure.

While the embodiment of the present invention as herein disclosed, constitutes a preferred form, it is to be understood that other forms might be adopted, all coming within the scope of the claims which follow.

What is claimed is as follows.

1. A switch and lamp holder unit comprising a metal socket member for receiving a lamp base having a metal sheath connected with one lead of the lamp filament and an end terminal connected with the other lead, said socket making electrical connection with the sheath; a switch comprising a hollow stationary contact and a hollow movable contact guided by the stationary contact; a rod slidably supported within the movable contact; abutments at each end of the rod for retaining the rod in assembled relation with the movable contact; a coiled spring about the rod, said spring having one end engaging one of the abutments of the rod and the other end engaging the movable contact, said spring operating to urge the said one abutment of the rod into engagement with the end terminal and the movable contact into engagement with the stationary contact, said spring and rod cooperating to conduct current from the movable contact to the end terminal; and means for actuating the movable contact relative to the rod to separate the contacts.

2. A switch and lamp holder unit comprising a metal socket member for receiving a lamp base having a metal sleeve connected with one lead of the lamp filament and an end terminal connected with the other lead, said socket making electrical connection with the sleeve; an insulating support; a stationary contact carried by the support; a plunger slidably guided by the stationary contact; a movable contact carried by the plunger; a rod having a head slidably supported within the movable contact, said head being adjacent the end contact of the base; a spring coiled about the rod and disposed between the head of the rod and the movable contact and operating to urge the head into engagement with the end contact of the base and the movable contact into engagement with the stationary contact, said spring and rod also operating to conduct current from the movable contact to the end terminal; and means for actuating the plunger to separate the contacts.

3. A switch and lamp holder unit comprising a metal housing having a socket portion formed

in one wall of the housing for receiving a lamp base having a metal sheath connected with one lead of the lamp filament and an end terminal connected with the other lead, said socket portion making electrical connection with the sheath; an insulating member fixed within the housing; a tubular stationary contact carried by the insulating member; a hollow plunger slidably supported by another wall of the housing and the stationary contact; a movable contact carried by the plunger; a rod slidably supported within the plunger; a coiled spring supported by the rod, said spring having one end engaging the movable contact and operating to urge the movable contact into engagement with the stationary contact, said spring and rod operating to conduct current from the movable contact to the end terminal; and means for actuating the plunger to move the movable contact from the stationary contact.

4. As an article of manufacture combined movable and stationary contacts and a carrier member for electric switches, said member comprising a flat plate of insulating material having an opening formed therein; a metal eyelet having a flange at one end, the shank of said eyelet extending through the opening and being spun over against the plate; a hollow member slidably supported in the shank of the eyelet; a second metal eyelet having a flange engaging one end of the hollow member, the shank of the second eyelet extending into the hollow member and being spun over an internal shoulder provided by the hollow member; a headed rod slidably supported in the second eyelet the shaft of the rod extending beyond the spun over portion of the second mentioned eyelet and being flared to prevent removal of the rod; and a spring disposed between the head of the rod and the flange of the second mentioned eyelet whereby the head of the rod is urged in one direction and the second mentioned eyelet and the plunger is urged in the opposite direction with the flange of said eyelet engaging the flange of the first mentioned eyelet when the carrier is supported in a fixed relation with respect to a current consuming device in an electric circuit.

5. A switch comprising in combination; a sub-assembly including a stationary contact, an actuator, a movable contact and a body for supporting the stationary contact, said stationary contact guiding the actuator and the movable contact into engagement with the stationary contact; means including part of the movable contact for securing the movable contact to the actuator, said movable contact, when secured, maintaining the movable contact, stationary contact and the actuator in the assembled relation with each other; a current consuming device having a terminal; a spring disposed between the terminal and the movable contact and operating to urge the movable contact into engagement with the stationary contact and to conduct current from the movable contact to the terminal; and means for moving the actuator to separate the contacts.

6. A switch comprising in combination; a sub-assembly including a stationary contact, an actuator, a movable contact and a body for supporting the stationary contact, said stationary contact guiding the actuator and the movable contact into engagement with the stationary contact; means including a portion of the movable contact for securing same to the actuator and for maintaining the movable contact and the actuator in the assembled relation with the station-

ary contact; a current consuming device having a terminal; a headed conducting stud having one end extending through the movable contact; a spring mounted on the stud, said spring having one end engaging the head of the stud and the other end engaging the movable contact to urge the movable contact into engagement with the stationary contact, said spring and stud conducting current from the movable contact to the terminal; and means moving the actuator movable contact relative to the stud to separate the movable contact from the stationary contact to open a circuit.

7. As an article of manufacture, combined movable and stationary contacts and a carrier member for electric switches, said carrier comprising a body of insulating material supporting a tubular stationary contact having one end thereof exposed at the front side of the body; an actuator extending through the stationary contact and having provisions intermediate its ends cooperating with the rear side of the body to limit the movement of the actuator in one direction; a movable contact having lateral extending portions carried by the actuator; means for securing the movable contact to the actuator, said movable contact, when secured, positioning the lateral extensions in a manner so to limit the movement of the actuator in the other direction; a contact stud slidably mounted in the movable contact; and a spring mounted on the stud, said spring operating, when the carrier is mounted in a fixed relation with respect to a current consuming device, to urge the contact stud in one direction and the movable contact and the actuator in the opposite direction with the lateral extensions of the movable contact engaging the stationary contact.

8. As an article of manufacture, combined movable and stationary contacts and a carrier member for electric switches, said carrier comprising a body of insulating material supporting a tubular stationary contact having one end thereof exposed at the front side of the body; an actuator extending through the stationary contact and having provisions intermediate its ends cooperating with the rear side of the body to limit the movement of the actuator in one direction; a movable contact having lateral extending portions carried by the actuator; means for securing the movable contact to the actuator, said movable contact, when secured, positioning the lateral extensions in a manner so to limit the movement of the actuator in the other direction; and a spring carried by the movable contact and operable when carrier is mounted in a fixed relation with respect to a current consuming device to urge the movable contact into engagement with the stationary contact and to conduct current from the movable contact to the current consuming device.

9. As an article of manufacture, combined movable and stationary contacts and a carrier member for electric switches, said carrier comprising a body of non-conducting material supporting a hollow stationary contact having a radial portion at the front side of the body; an insulating sleeve axially guided by the stationary contact; a tubular contact carried by the sleeve, said sleeve having a radial portion at one end adapted to engage the radial portion of the stationary contact and having provisions at the other end cooperating with provisions provided by the sleeve for retaining the sleeve in assembled relation with the plunger; a headed member

slidably supported in the tubular contact; an abutment carried by the headed member at the rear of the tubular contact for retaining the member in assembled relation with the tubular contact; and resilient means disposed between the head of the member and the radial portion of the tubular contact whereby the headed member is urged in one direction and the tubular contact in the opposite direction with the radial portion of the tubular sleeve engaging the stationary contact when the carrier is supported in a fixed relation with respect to a current consuming device in an electric circuit.

10. A switch and lamp holder unit comprising a metal socket member for receiving a lamp base having a metal sleeve connected with one lead of the lamp filament and an end terminal connected with the other lead, said socket making electrical connection with the sleeve; a switch

comprising a stationary contact and a movable contact guided by the stationary contact; a conducting member slidably supported relative to the movable contact; means carried by the conducting member for maintaining the movable contact and the conducting member in assembled relation; a conducting spring having one end electrically connected to one end of the conducting member and having the other end engaging the movable contact, said spring operating to urge said one end of the conducting member into engagement with the end terminal and the movable contact into engagement with the stationary contact, said conducting spring or conducting member being capable of conducting current from the movable contact to the end terminal; and means for actuating the movable contact relative to the conducting member to separate the contacts.

ARNOLD A. BLUEMLE.
